UNITED STATES PATENT OFFICE.

JOSEPH SACHS, OF HARTFORD, CONNECTICUT.

SWITCH-OPERATING MECHANISM.

Application filed December 12, 1921. Serial No. 521,775.

To all whom it may concern:

Be it known that I, JOSEPH SACHS, a citizen of the United States, residing at Hartford, in the county of Hartford and State 5 of Connecticut, have invented a new and useful Improvement in Switch-Operating Mechanism, of which the following is a specification.

This invention relates to a mechanism 10 which is especially designed for operating safety switches, that is, those knife blade switches which are enclosed in casings and are operated by a handle on the outside, but the mechanism is also adapted for actuating 15 other types of switches.

The object of the invention is to provide 20 a self-contained operating mechanism of this character that is compact and durable, easy to apply to the switch and smooth in 25 operation, and which will cause the blades to both make and break the circuit quickly when the handle is turned for closing and opening the circuit, the mechanism being particularly adapted for operating the larger 30 sizes of such switches but of course is applicable to small switches.

This object is attained by forming a unit 35 of three members, one, the spindle member which is adapted to be slipped into connection with the switch blade oscillating spindle, another, the handle member, which has the operating lever, and the third, an intermediate member that is turned by the handle and that through a torsion spring which 40 is coiled about the spindle, holds the spindle member until the handle has moved the necessary distance to tension both the torsion spring and a spring connected with the intermediate member and carry the latter 45 spring past center so as to release the parts and allow the spindle member to be thrown by the combined forces of both springs, thus causing a very quick make or break according to the direction in which the handle is turned.

In the accompanying drawings Figure 1 shows a side elevation of an enclosed safety switch provided with an operating mechanism that embodies the present invention, 50 with the handle in the position occupied when the circuit is open. Fig. 2 shows a horizontal section of the operating mechanism on the plane of its axis. Fig. 3 shows a plan of the mechanism attached to the 55 side of the switch casing. Fig. 4 shows a

face view of the mechanism with the parts in the positions occupied when circuit is open. Fig. 5 is a similar view with the parts in the positions occupied when the handle is turned so as to tension the torsion and main 60 springs and just before the latter swings past center and releases the parts so that the blade will be thrown by both springs into engagement with the contact clip. Fig. 6 shows the parts in the positions occupied 65 after the blade has been thrown by the springs into engagement with the contact clip. Fig. 7 shows the handle moved and the springs tensioned for opening the circuit. Fig. 8 is a perspective view of the 70 active parts looking from the outside with the locking plate lifted. Fig. 9 is a perspective view of the active parts looking from the inside. Fig. 10 is a perspective view of the spindle member. Fig. 11 shows a perspective view of the intermediate member 75 looking from the inside. Fig. 12 is a perspective view looking from the inside of the handle member.

The switch mechanism which forms the 80 subject of this invention is shown as applied to the outside of the casing 1 of an enclosed safety switch. But one swinging contact blade 2 of the switch is indicated, which blade is adapted to be thrown into and out of 85 engagement with the terminal clip 3 that is mounted on the under side of an insulating block 4 fastened in the casing. In the type of switch illustrated the blade is swung by a plate 5 that has a hook 6 which is adapted 90 to be engaged by the crank spindle 7 in a manner common to this style of switches. These parts being well known, further detailed description is unnecessary.

In the unitary mechanism which forms 95 the subject of this invention the spindle member extends through an opening in the casing with its axis in line with the axis of the switch blade. This member in the construction shown has a hollow hub 8 on the 100 inside with a slot 9 in its side and is so formed that the hub may be slipped upon the outer end of the crank spindle, through the opening in the side of the casing with the bend of the crank passing through the 105 slot in such manner that when this member is rotated the crank spindle will be turned with it. At the middle the spindle member has a flange 10 with a notch in its edge that provides two walls 11 and 12. On the out- 110

side the spindle member has a hollow hub 13 with a slot in its side which provides two walls 14 and 15.

The intermediate member is in the form 5 of a sleeve 16 that is adapted to fit and turn upon the periphery of the hub 13 of the spindle member. Projecting from one side at the inner end of the intermediate member and between the walls 11 and 12 10 of the spindle member is a lug 17 pivoted to which is the head of a rod 18 that extends downward and passes loosely through a hole 19 in the cover plate 20 which is fastened to the casing over the operating 15 mechanism. On the rod near its outer end inside of the cover plate is a loose washer 21 and thrusting between this washer and the head of the rod is a spiral spring 22. Opposite the lug the outer edge of the intermediate member is notched to provide 20 walls 23 and 24 and the inner edge of this member is notched to form walls 25 and 26.

The handle member with the operating lever 27 has a hub 28 fitted to turn on the 25 outside of the intermediate member. The outer edge of the hub of the handle member is notched to provide walls 29 and 30 and the inner edge of the hub has a notch with walls 31 and 32 and a notch with walls 30 33 and 34. The lug 17 of the intermediate member projects into the notch between the walls 31 and 32.

Coiled about the end of the crank spindle in the spindle member is the torsion 35 spring 35. The ends of this spring project radially into notches in the members and are so torsioned that they tend to spread or unwind. The inner end 36 of the torsion spring normally presses against the wall 34 40 of the notch in the inner edge of the handle member, the wall 25 of the notch in the inner edge of the intermediate member and the wall 15 of the slot in the spindle member. The outer end 37 of the torsion spring 45 normally presses against the wall 29 of the notch in the outer edge of the handle member, the wall 24 of the notch in the outer end of the intermediate member and the wall 14 of the slot in the spindle member.

50 With the switch open the members are in the relations illustrated in Fig. 4. Upon turning the handle to close the switch the inner end of the torsion spring is engaged by the wall 34 and carried so as to wind up 55 and increase the tension of the torsion spring, for the outer end of the spring is held at this interval by the wall 24 of the intermediate member. During a continuation of this movement the wall 31 of the notch 60 in the inner edge of the handle member engages with the lug 17 projecting from the intermediate member and turns the latter member and compresses the spiral spring. At this time the engagement of the lug 65 with the wall 12 turns the spindle member

and moves the spindle and switch blade a short distance. The tension of the spiral spring increases until the intermediate member is turned so that the pivotal connection of the spring rod with the lug is on the 70 center line between the axis of the switch and the pivotal point of the outer end of the spring rod where it passes through the hole in the cover plate, which position is illustrated in Fig. 5. At this time both 75 the torsion spring and the spiral spring are under maximum tension and there is a space between the lug and the wall 32 on the handle member. When the handle is turned sufficiently to carry the pivotal point 80 of the spring rod with the lug past the center, the spiral spring throws the intermediate member, and the engagement of the lug 17 with the wall 12 of the notch in the edge of the spindle member rotates that 85 member. This movement of the intermediate member releases the end 37 of the torsion spring which is in engagement with the wall 14 of the slot in the spindle member so that spring aids in throwing the 90 spindle member. Thus after the handle has been turned past the center the spindle member is thrown by the united forces of the spiral spring and the torsion spring, and the switch blade is snapped into 95 engagement with the terminal clip, as shown in Fig. 6.

To open the switch the handle is turned in the opposite direction. The first movement of the handle by the engagement of 100 the wall 32 with the lug 17 turns the intermediate member and compresses the spiral spring. At the same time the wall 29 engages the end 37 of the torsion spring and increases the tension of that spring. 105 Near the end of this interval the lug engages the wall 11 on the spindle member and turns that member positively so as to start the blade from the clip. The parts are then in the position shown in Fig. 7. Further movement of the handle carries the spiral spring past the center so that it can 110 throw the intermediate member and complete the opening of the switch as shown in Fig. 4. The torsion spring being released 115 by the throwing of the intermediate member adds its force to the throwing of the spindle member, thus both the opening and closing movements of the switch blade are affected by the combined forces of the two 120 springs. While the handle member has some lost motion between it and the other parts to permit the quick movements of the switch blade when snapped the torsion spring retains it firmly in position at both 125 limits of its path.

The cover plate has perforations 38 and 130 inside of the cover plate mounted on the end of the crank spindle and over the hub of the spindle member so as to turn there-

with is a locking plate 39 with openings 40 designed to register with the perforations in the cover plate. The edge of the handle member may also have notches 41 that register with the locking plate perforations. These openings are provided so that if desired the loop of a padlock or seal may be passed through them to lock the switch either in its opened or closed position.

10 1. I claim:

15 1. A switch operating mechanism comprising a rotatable member having means for attachment to a switch spindle, a rotatable member having an operating handle, a rotatable intermediate member, a torsion spring coiled within the spindle member and having its ends engaging all of said members, and a spiral spring with its outer end adapted to be pivotally held and its 20 inner end connected with the intermediate member on one side of the center line between the axis of the mechanism and the point of pivotal connection of the outer end of the spring.

25 2. A switch operating mechanism comprising a rotatable member having means for attachment to a switch spindle, a rotatable member having an operating handle, a rotatable intermediate member, a torsion 30 spring coiled within the spindle member and having its ends engaging all of said members, and a spiral spring with its outer end adapted to be pivotally held and its inner end connected with the intermediate member on one side of the center line between the axis of the mechanism and the point of pivotal connection of the outer end of the spring, both of said springs being tensioned in the same direction by the movement of the handle and both acting to throw the spindle member when the pivotal connection of the spiral spring with the intermediate member is moved past said center line.

35 3. A switch operating mechanism comprising a rotatable member having means for attachment to a switch spindle, a rotatable member having an operating handle, a rotatable intermediate member, a torsion 40 spring coiled within the spindle member and having its ends engaging all of said members, and a spiral spring with its outer end adapted to be pivotally held and its inner end connected with the intermediate member on one side of the center line between the axis of the mechanism and the point of pivotal connection of the outer end of the spring, both springs being tensioned by the movement of the handle and the torsion spring being held by the intermediate member until after the handle has moved the pivotal point of connection of the spiral spring with the intermediate member past said center line.

45 4. A switch operating mechanism comprising

ing a rotatable member having means for attachment to a switch spindle, a rotatable member having an operating handle, a rotatable intermediate member, a torsion spring coiled within the spindle member and having its ends engaging all of said members, and a spiral spring with its outer end adapted to be pivotally held and its inner end connected with the intermediate member on one side of the center line between the axis of the mechanism and the point of pivotal connection of the outer end of the spring, both springs being tensioned by the movement of the handle and both being released to throw the spindle member 80 by the swinging of the spiral spring past said center line.

5. A switch operating mechanism comprising a rotatable member having means for attachment to a switch spindle, a rotatable member having an operating handle, a rotatable intermediate member, a torsion spring coiled within the spindle member and having its ends engaging all of said members, and a spiral spring with its outer 90 end adapted to be pivotally held and its inner end connected with the intermediate member on one side of the center line between the axis of the mechanism and the point of pivotal connection of the outer end of the spring, both springs being tensioned by the handle and when released co-operating to throw the spindle member and the torsion spring holding the handle firmly at both limits of its movement.

6. A switch operating mechanism comprising a rotatable member having means for attachment to a switch spindle, a rotatable member having an operating handle, a rotatable intermediate member, a casing enclosing said members, a torsion spring coiled within the spindle member and having its ends engaging all of said members, and a spiral spring with its outer end adapted to be pivotally retained by said casing and its 105 inner end connected with the intermediate member on one side of the center line between the axis of the mechanism and the point of pivotal connection of the outer end of the spring.

7. A switch operating mechanism comprising a rotatable member having means for attachment to a switch spindle, a rotatable member having an operating handle, a rotatable intermediate member, a casing enclosing said members, a locking plate in the casing and connected to rotate with the spindle member, a torsion spring coiled within the spindle member and having its ends engaging all of said members, and a 110 spiral spring with its outer end adapted to be pivotally retained by said casing and its inner end connected with the intermediate member on one side of the center line between the axis of the mechanism and the 115

120

125

130

point of pivotal connection of the outer end of the spring.

8. A switch operating mechanism comprising a rotatable tubular member having a slot adapted to receive a crank spindle, a rotatable member having an operating handle, a rotatable intermediate member, a torsion spring coiled within the spindle member and having its ends engaging all 10 of said members, and a spiral spring with its outer end adapted to be pivotally held and its inner end connected with the intermediate member on one side of the center line between the axis of the mechanism and the 15 point of pivotal connection of the outer end of the spring.

9. A switch operating mechanism comprising a rotatable tubular member having a slot adapted to receive a crank spindle, 20 a tubular intermediate member mounted to rotate on the spindle member, a tubular handle member mounted to rotate on the intermediate member, means projecting from the intermediate member and having a lost motion engagement with the handle member and the spindle member, a torsion spring coiled within the spindle member and having its ends engaging all of said members, and a spiral spring with its outer end adapted to be pivotally retained by a fixed casing and its inner end connected with said means projecting from the intermediate member on one side of the center line between the axis of the mechanism and the 25 point of pivotal connection of the outer end of the spring with the casing.

10. A switch operating mechanism comprising a rotatable tubular member having a slot adapted to receive a crank spindle, 40 a tubular intermediate member mounted to rotate on the spindle member, said intermediate member having notches in its ends, a tubular handle member mounted to rotate on the intermediate member, said handle 45 member having notches in its ends, a torsion spring coiled within the spindle member and having its ends extending into the notches of said members, means projecting from the intermediate member and extending into a 50 slot in the handle member, and a spiral spring with its outer end adapted to be pivotally retained by an enclosing casing and its inner end connected with said means projecting from the intermediate member 55 on one side of the center line between the axis of the mechanism and the point of pivotal connection of the outer end of the spring with the enclosing casing.

11. A switch operating mechanism comprising a spindle member, a handle member, an intermediate member, a spring holding all of said members in definite relation in the on and off positions, and an actuating spring, both of said springs being tensioned by the movement of the handle and

coacting when released to throw the spindle member in its on and off movements.

12. A switch operating mechanism comprising a spindle member, a handle member, an intermediate member, said handle member having a lost motion engagement with the intermediate member, and the intermediate member having a lost motion engagement with the spindle member, a spring holding said members in definite relation in the on and off positions, and an actuating spring, both of said springs being tensioned by the movement of the handle and coacting when released to throw the spindle member in its on and off movements 75 independent of the further movement of the handle member.

13. A unitary self-contained switch operating mechanism adapted to be applied to the casing of an enclosed switch comprising means for connecting said mechanism to the switch, an operating handle, resilient actuating means arranged between the handle and said connecting means, and means adapted to tension and release the said resilient actuating means and causing said latter means to throw the switch connecting means in both on and off directions.

14. A unitary self-contained switch operating mechanism adapted to be applied to the casing of an enclosed switch comprising means for connecting said mechanism to the switch, an operating handle, resilient actuating means arranged between the handle and said connecting means, and means adapted to tension said actuating means and positively move the switch connecting means, and for releasing the said actuating means and permitting it to throw the switch connecting means in both on 95 and off directions.

15. A unitary self-contained switch operating mechanism adapted to be applied to the casing of an enclosed switch comprising means for connecting said mechanism to 110 the switch, an operating handle, resilient actuating means arranged between the handle and said connecting means, and means controlled by the movements of the handle for first causing the switch connecting means to be moved positively and then permitting it to be thrown by said resilient actuating means in both the on and off movements.

16. A switch operating mechanism comprising a rotatable member having means for attachment to a switch spindle, a rotatable member having an operating handle, a rotatable intermediate member, a spring engaging all of said members and normally 125 holding them in definite relation, and a spring with its outer end pivotally retained and its inner end connected with the intermediate member on one side of the center line between the axis of the mechanism and 130

the point of pivotal connection of the outer end of the spring.

17. A switch operating mechanism comprising a rotatable member having means for attachment to a switch spindle, a rotatable member having an operating handle, a rotatable intermediate member, said members having a common axis, a spring directly associated with all of said members and normally holding them in definite relation, and an actuating spring adapted to be first tensioned and then released by the movement of the handle member in both the on and off movements.
18. A switch operating mechanism comprising a rotatable member having means for attachment to a switch spindle, a rotatable member having an operating handle, a rotatable intermediate member, said members being concentrically mounted on each
19. A switch operating mechanism comprising a rotatable member having means for attachment to a switch spindle, a rotatable member having an operating handle, a rotatable intermediate member, said members being concentrically mounted, a coiled spring having its ends engaging all of said members and normally holding them in definite relation, and a spring connected with the intermediate member and adapted to be tensioned and released for throwing the intermediate member by the movement of the handle in both directions.

JOSEPH SACHS.
